SAFETY REVERSIBLE WINDOW

Olien Polson, Hugo W. Walters, Nels O. Carlson,
Fred Ekholm, Arthur O. Norén, and Knut
Anderson, Chicago, Ill.

Application March 17, 1933, Serial No. 661,402

2 Claims. (Cl. 20—49)

This invention relates to a new and improved safety reversible window and has for one of its principal objects the provision of a window, the sashes of which can be readily reversed whereby both faces of the glass may be simply and efficiently cleaned or washed without the necessity of getting outside the window with consequent annoyance, exertion and danger.

Another important object of this invention is to provide a reversible window which shall be particularly safe on account of being proof against wind and weather as, for example, any tendency of high winds to blow the sash inwardly or to blow rain water, cold winds or the like through the space between the sash and the frame.

Another important object of the invention resides in the provision of a safety reversible window wherein the usual sash cords and weights are eliminated without, however, impairing the efficiency of the sash, whereby the window may be opened by sliding the same up and down relatively in the frame, and which window, furthermore, includes a provision for automatically positioning the sash in any desired position with respect to the frame when moved up or down.

A still further important object of the invention is to provide means in a reversible window for automatically locking the sash in position with respect to the frame when the same is moved inwardly into full or part of a reversed position for cleaning or ventilating purposes.

A still further important object of the invention is the provision in a safety reversible window of means for affording adequate ventilation of any degree whenever desired, and additional means for locking the sash in room ventilating position while at the same time rendering the same proof against burglars, sneak thieves, or other intruders.

A further object of the invention resides in the provision of means for readily holding curtains or drapes away from the window frame in such a position that they will not be in the way when it is desired to open the windows for cleaning, ventilation or other purposes. This means is automatically adjustable to various widths of window frames.

Another and still further important object of the invention is to provide a novel means for locking the window at a point adjacent the meeting strips of the sashes which locking means further includes an improved ventilating and burglar-proof device.

Other and further important objects of the invention will be apparent from the disclosures

in the accompanying drawings and following specification.

The invention, in a preferred form, is illustrated in the drawings and hereinafter more fully described.

In the drawings:

Figure 1 is an elevational view of the improved safety reversible window of this invention, showing one of the operating means therefor.

Figure 2 is a sectional view taken on the line 2—2 of Figure 1, looking in the direction indicated by the arrows.

Figure 3 is a perspective view showing the novel combination of weather stripping and slide whereby a pivoted action of the sash with respect to the frame is permitted.

Figure 4 is a detail sectional view, illustrating more fully the pivot for a sash and the automatic locking means associated therewith.

Figure 5 is a rear view of a portion of the automatic sash locking means shown in Figure 4.

Figure 6 is a sectional view of the combined pivot and locking means, the same being taken on the line 6—6 of Figure 4.

Figure 7 is a side elevation of the window, showing the sash swung inwardly for washing and ventilating purposes.

Figure 8 is a detail view, partly in section, of the means for automatically positioning the sash with respect to the frame when moved up or down.

Figure 9 is a detail view of the upper end of the upper sash, showing its relation to the lintel.

Figure 10 is a sectional view of the meeting rails of the upper and lower sashes, showing a portion of a ventilating and burglar-proofing appliance.

Figure 11 is a sectional view of the bottom rail of the lower sash, showing its weather-proof cooperation with the window sill.

Figure 12 is an elevational view of a combination burglar-proofing and ventilating appliance positioned on the upper sash and adapted to cooperate with the lower sash.

Figure 13 is a side elevation, showing the lower sash adjusted relative to the upper sash for ventilating and burglar-proofing purposes.

Figure 14 is a top plan view of the improved means for holding the window curtains or drapes away from in front of the frame, thereby providing ready operation of the sash.

Figure 15 is a front elevation of the window, showing the drape holding means in operation and the sash opened.

Figure 16 is a sectional view taken on the line 55

16—16 of Figure 14, looking in the direction indicated by the arrows.

Figure 17 is a front view of the device shown in Figure 16.

5 Figure 18 is a detail view, partly in section, showing a modified locking and ventilating means for the sash adjacent the meeting strips.

10 Figure 19 is a top plan view of the structure, showing in Figure 18 the operation thereof, being illustrated in dotted lines.

15 As shown in the drawings:

The reference numeral 14 indicates generally a window sill having a lintel 16 and with stiles 18 joining the two to form a window frame. The stiles 18 are provided with inner retaining strips 20 and outer retaining strips 22 for the purpose of retaining the sashes in position in the frame.

20 Slidably mounted in the frame is an upper sash having a top rail 24, side rails 26 and a meeting rail 28. A lower sash is also provided having a meeting rail 30, side rails 32 and a bottom rail 34.

25 Fixed into the side rails of each of the sashes as best shown at 36 in Figure 3 is a portion of a weather-strip element preferably made of sheet metal or the like which has one edge 38 bent over and forced into a corresponding slot in the sash element 32. Adapted to cooperate with this weather-strip element 36 is a corresponding weather-strip element, preferably made in one piece but formed in several portions comprising an outer portion 40, an inner portion 42, and side elements 44 and 46 respectively, all of which elements are formed from an integral strip as best shown in Figures 2 and 3. Adjacent the bottom of the sash element 32, the member 36 is pivotally mounted in the corresponding weather-strip member 40—46 by means of a pivot pin or the like 48. The weather-strip elements 40—46 are preferably of approximately the same height as the height of a sash as best shown by the dotted lines in Figure 7, and are slidably mounted in corresponding notches or grooves formed in the stile 18 in conjunction with the retaining strip 28 as best shown in Figure 2. In this manner, the sashes may be moved up and down in the frame, the weather-strip elements moving along therewith.

30 In order to prevent a sash, particularly the lower one, from falling or being blown inwardly by means of air pressure or the like, a latch element 50 is provided which fits through corresponding openings in the weather-strips as shown in Figure 2 and which is normally impelled into latching position by means of a helical spring 52 positioned there-behind in its mounting in the sash member 32. A push-button 54 positioned in a suitable casing 56 is fixed in the sash for manual operation for retracting the latch 50 when desired.

35 60 In order to lock the sash assembly in any desired position relative to the frame when the sash is moved inwardly about the pivot 48, a locking plate 58 is provided mounted on the outer end of the pivot rod 48 as best shown in Figure 4, and adapted to cooperate with a shoulder 60 formed on the rod or shaft 48 is a corresponding shoulder 62 which is formed on a sleeve 64 which sleeve, in turn, forms part of a casing 66 in which the shaft 48 operates. This casing 66 is built into 40 the sash at its lower outer corner, and in addition to forming a housing for the pivotal mounting, also provides quite a reinforcing structure for the corner of the sash. It will be obvious that when the sash is rotated forwardly about the pivot 70 point 48, for example, as shown in Figures 3, 7,

and 13, the cooperation of the shoulders 60 and 62 will force the plates 58 outwardly, there being one on each side of the sash, into locking contact with the inner face of the stile 18, whereby the sash itself, with its weather-stripping and appurtenances, is thereupon locked in that position and cannot be moved either upwardly or downwardly until it is again restored to its normal vertical position with respect to the window frame whereupon a pin 68 mounted on the rod 48 (Figure 5) will ride inwardly on a shoulder 70 formed on the casing 66 and release the plate 58 from gripping contact with the stile 18.

10 15 20 As best shown in Figure 6, a portion of the rod 48 inside the housing 66 is cut away to form a stop 90 and a corresponding extension is formed in the inner face of the housing or sleeve 66 as best shown at 92, which extension, when the sash is moved into horizontal position, will contact with the stop 90, thereby preventing any further downward movement of the sash.

25 In order to maintain the sash in desired position with respect to the frame and lintel, a friction gripping means is provided as best shown in Figure 8. This comprises essentially a roller 25 or the like 72 positioned in a housing 74 which housing is fitted into a corresponding opening in the stile 18. In the housing is a leaf-spring 76 which acts against one cylindrical face of the roller 72, this leaf spring being positioned at an angle, so that when the roller is forced downwardly, a corresponding tension of the spring results. Adapted to act against the cylindrical face of the roller 72 is the element 46 of the weather-strip, and it will be evident that upon raising the sash, the roller is forced upwardly out of contact with this element 46 and an upward movement of the sash is, thereupon, readily permitted. Upon a downward movement, however, the roller is forced downwardly, and on account of the position of the leaf-spring 76, a gripping action results which retards such downward movement, and the relation of the spring to the other parts and the stiffness thereof is such that while the sash is held in position against the action of gravity, it can be readily moved downwardly by a suitable pushing force.

30 35 40 45 50 As best shown in Figure 9, the top rail 24 of the upper sash is weather-stripped with respect to the lintel 16 by means of a strip 78 of metal or other suitable material formed in the corresponding grooves in the lintel 16 and rail 24, the metal strip being preferably held in position by nails or the like 80.

55 60 65 70 75 In Figure 10 is shown a method of weather-proofing the meeting rails wherein a weather-strip 82 is attached to the rail 30 and a corresponding strip grooved at its bottom, as shown at 84, is attached to the sash rail 28. The line of juncture between the lower sash rail 34 and the sill 14 is protected by means of a weather-strip 86, shaped as best shown in Figure 11, attached to the sill itself by means of nails or the like 88.

80 85 90 95 100 As best shown in Figures 12 and 13, an application for permitting of an inward opening of the lower sash 32 a slight distance for the purpose of ventilation, while at the same time locking the same in this position, is provided. This consists of a strip 94 hingedly mounted to a plate 96 fixed on the face of the sash rail 26, and which strip has a groove 98 formed therein, widened at 100 to permit the entry of the head 101 of a correspondingly shaped latching element 102 fixed to the inner face of the upper edge of the lower sash 105 110

32. When the head of the element 102 is fitted into the groove 98 of the metal strip 94, it will be obvious that the lower sash will be permitted only a correspondingly limited movement about its 5 pivot as best shown in Figure 13. This allows of free ventilation, while at the same time preventing unauthorized entry through the window.

A modified form of the combination ventilating and locking means shown in Figures 12 and 13 is 10 presented in Figures 18 and 19 wherein the meeting strip 28 is provided with an upstanding latch element 104 fastened thereto and which has a head 106 for the purpose of loosely retaining a locking plate 108 thereon. This locking plate has 15 a slot 110 therein which slot terminates in an opening 112, the opening being substantially circular, but having one side 114 restricted to an elliptical curvature. This opening is large enough to encompass the base of the element 104 and 20 the base of a corresponding latching element 116, which is likewise provided with a locking head 118.

A rotation of the plate 110 about the elements 104 and 116 into a position shown in the dotted 25 lines in Figure 19 will, on account of the partially restricted circumferential portion 114 of the opening 112, bring these two elements into locking relationship with each other, thereby preventing opening of the window.

30 Additionally, a movement of the element 116 in the slot 110 when the plate 108 is in the position shown in the full lines in Figure 19 will result in an opening of the window sashes into a position similar to that shown in Figure 13, allowing 35 ventilation but prohibiting unauthorized entry.

In order that the sashes may be moved into open position as shown in Figures 7 and 15 without interfering with draperies or the like 120, a 40 supporting element is provided for retaining the draperies out of the way of the sashes.

This supporting element is best shown in Figure 14 and comprises a rod 122 telescopically fitted 45 into a tube 124, both the rod and the tube having at their outer ends a bracket 126 which supports the curtain in an out of the way position as shown in Figure 15.

A clamping element 128 is positioned around 50 the tube 124 as best shown in Figures 14 and 16, and an operating handle 130 is pivotally mounted 55 in this clamping element, the same being provided with a heel 131 which, when the handle is turned to the right will lock the heel against the tube 124, thereby retaining the entire bracket in 60 desired position in a window recess or frame. A link 132 is pivotally mounted to the handle 130 which link operates in a slot in the rod 122 and abuts in stopping relationship against the end of the slot as best shown in Figure 17. This supporting bracket can be readily removed when not 65 in use and may obviously be adjusted to any width of window in a very short space of time. Furthermore, it will occupy only a very small space when not in use.

65 It will be evident that herein is provided a safety reversible window which combines many advantages, namely those of ready accessibility

for washing of both faces of the glass, suitable weather-stripping against rain, winds and the like, provision of desirable means for ventilation and accompanying protection against burglaries as also other important features, such as automatic locking when closed, automatic positioning when open, and automatic self-support whereby sash cords and weights are eliminated.

We are aware that many changes may be made, and numerous details of construction varied 10 throughout a wide range without departing from the spirit of this invention, and we, therefore, do not purpose limiting the patent granted hereon otherwise than as necessitated by the prior art.

15 We claim as our invention:

1. In a window frame, upper and lower sashes, 20 grooves in the frame, stiles and weather-strips on the sashes, portions of said weather-strips slidably mounted in the grooves, and other portions of the weather-strips affixed to the sashes, together with a pivotal connection between the sash weather-strips and the frame weather-strips whereby the sash may be tilted inwardly, said pivotal connection including means for locking the sash in position with respect to the frame upon such inward tilting, said means comprising a 25 shaft, a plate on one end of the shaft adapted to contact with the face of the stile, a housing in the sash through which the shaft passes, and co-operating cam means on the shaft and housing 30 for forcing the plate into locking relationship with the stile upon downward movement of the sash, together with further means on the shaft and its housing for releasing the plate from locking position upon upward movement of the sash, 35 said means comprising a pin mounted in the shaft, and a corresponding cam face on the shaft housing.

2. In a window frame, upper and lower sashes, 40 grooves in the frame, stiles and weather-strips on the sashes, portions of said weather-strips slidably mounted in the grooves, and other portions of the weather-strips affixed to the sashes, together with a pivotal connection between the sash weather-strips and the frame weather-strips 45 whereby the sash may be tilted inwardly, said pivotal connection including means for locking the sash in position with respect to the frame upon such inward tilting, and stop means for limiting the downward movement of the sash to a 50 horizontal position, together with further stop means for arresting undesirable downward movement of the sash in a vertical plane, said means comprising a roller mounted in a recess in the stile of the window frame with its cylindrical face 55 bearing against a portion of the sash weather-stripping, and spring means acting against the roller for forcing the same into gripping relationship with the weather-strip upon the initiation of a downward movement of the sash.
